(57) **CLAIM**

The ornamental design for the accordion dish-drying rack with utensil holder, as shown and described.

DESCRIPTION

FIG. 1. is a perspective extended view of the accordion dish-drying rack with utensil holder showing my new invention;

FIG. 2. is a top plan extended view of my new invention shown in FIG. 1;

FIG. 3. is a bottom plan extended view of my new invention shown in FIG. 1;

FIG. 4. is a left side elevational extended view of my new invention shown in FIG. 1; Right side being a mirror image;

FIG. 5. is a front elevational view of my new invention shown in FIG. 1;

FIG. 6. is a rear elevational extended view of my new invention shown in FIG. 1;

FIG. 7. is a perspective collapsed view of my new invention shown in FIG. 1;

FIG. 8. is a top plan collapsed view of my new invention shown in FIG. 1;

FIG. 9. is a bottom plan collapsed view of my new invention shown in FIG. 1;

FIG. 10. is a left side elevational collapsed view of my new invention shown in FIG. 1; Right side being a mirror image; and,

FIG. 11. is a rear elevational collapsed view of my new invention shown in FIG. 1.
